JAMES R. LEWIS, OF CHICAGO, ILLINOIS.

TOOL FOR SURFACING JOURNAL-BOX ENDS.

1,413,920.

Specification of Letters Patent. Patented Apr. 25, 1922.

Application filed October 2, 1920. Serial No. 414,321.

To all whom it may concern:

Be it known that I, JAMES R. LEWIS, a citizen of the United States, residing in Chicago, Cook County, Illinois, have invented certain new and useful Improvements in Tools for Surfacing Journal-Box Ends, of which the following is a specification.

My invention relates to tools for reforming the ends of journal boxes after relining the same, as by Babbitt metal, by cutting away superfluous metal there so as to make the bearing conform to the shape of the journal at the journal box ends.

In automobile practice the main crank shaft bearings require relining with Babbitt metal from time to time. In such practice after the babbitt is poured into the journal box frames respectively a cutting tool is applied and the babbitt is resurfaced longitudinally to conform to the cylindrical shape of the journals respectively. After this has been done it is found that there is still a considerable quantity of the Babbitt metal projecting longitudinally of the bearing at the ends, which excess metal is in the form of a half ring of irregular shape and of varying width in the diametric directions, it being integral with the lining and substantially adhering to the iron casting constituting the frame of the box.

Before the crank can be applied to these bearings this excess metal at the ends of the box must be removed. The operation heretofore employed for this purpose consists in chipping the metal away with a cold chisel and hammer until the desired surface is approximately reached and then using a hand file and scraper to give the bearing the desired exact length defined by the length of the journal. Furthermore, these crank shaft journals are invariably provided with an annular collar or stepped-up offset portion which merges gradually into the bearing surface of the journal, the metal there being known as a fillet, the fillets being at the ends respectively of each journal. To enable the shaft to come down properly upon the main surface of the bearing it is necessary to remove the corner metal at the ends of the box, and in such a nice and exact way as to give the fillets on the journal the proper

bearing surfaces in the box, consideration being had of the fact that if the amount of metal removed be not of the proper amount and at the proper places the crank shaft will either bind or will have longitudinal play. The operation heretofore of cutting away this corner metal to accommodate the fillet mentioned consists in using first a half round file for rough work and then a hand scraper, and in making the desired fit the fillet portions of the bearings are coated with some substance such as chalk, lamp black or Prussian blue in pasty form and the shaft then applied to the bearings and the shaft rocked or rotated, whereupon on removal of the shaft the bearings indicate the high places thereon, and these are, one by one, removed by the scraper, the operation being repeated until finally the shaft fits down accurately, that is, if the work has been carefully done by a skilled mechanic.

In this connection it is pointed out that the operation just mentioned is rendered more than ordinarily difficult from the fact that all of the three, four or more aligning bearings must be worked away substantially simultaneously so that the shaft will come down substantially equally at each end. It needs hardly to be mentioned that this method of fitting these journals to the boxes is exceedingly costly of time and labor, and that where the work is attempted to be performed by any one but a skilled mechanic it is unsatisfactory in the end.

My present invention has for its objects the provision of a simple, relatively cheap, strong and durable tool which may be easily and conveniently applied and operated by anyone having even a rudimentary knowledge of mechanics, and which will effectively, and in an exceedingly brief period of time, at once remove the excess lining metal overflowing the box frame and cut a true and accurate surface for the fillet, thus saving much expense and producing what would be mechanically considered a perfect job.

In the accompanying drawings, which form a part of this specification, Figure 1 is a fragmentary top plan of what may be considered an automobile journal box frame

as it ordinarily appears after the babbittting operation, my preferred form of resurfacing device, with a part of the pilot bearing member broken away, being shown in operative position; Fig. 2 is a medial vertical section of the parts of Fig. 1 as on the line 2—2 thereof; Fig. 3 is a vertical section on the line 3—3 of Fig. 2 or a horizontal section on the line 3—3 of Fig. 1; Fig. 4 is a face view of the cutter, the shaft being sectionally shown; and Fig. 5 shows a horizontal top view, similar to that of Fig. 1, of fragments of a babbitted bearing box with my improved tool in operative position, the cutter being diagrammatically shown, this figure showing a modification of the pilot stem holding means.

The bearing box frame 10 and the babbitt lining 11 are to be considered of ordinary and usual form, and the excess end metal at 12 is shown as an irregular overlapping mass, as it usually appears.

My improved resurfacing tool as illustrated comprises a cylindrical shaft 15 having a cross piece or handle 16, another cross piece or locking rod 17, preferably held tightly in a diametric hole in the shaft, and the cutter 18, which has a diametric recess at 19 adapted to accommodate the cross pin 30 17, the cutter 18 being sufficiently loosely mounted upon the shaft so that it may readily be removed. The shaft 15 extends forward beyond the cutter, the part beyond the cutter constituting a pilot stem 20. When the shaft is rotated in the cutting operation the pin 17 not only carries the cutter with the shaft but conveys to the cutter the thrust or pressure exerted by the hand which feeds the cutter into the work.

40 The cutter 18 is a steel cylindrical device having a plurality of teeth 22, the teeth respectively having a cutting edge at 23 which cutting edge is in a plane substantially perpendicular to the axis of the shaft 15, and 45 this cutting edge 23 is adapted to operate upon the surplus metal 12, shaving it off until it is all removed or until as much thereof is removed as may be desired. These cutting edges 23 are therefore adapted to 50 shorten the babbitt of the bearing until it fits snugly between the shoulders of the journal. The cutter is also provided with a forwardly projecting part 24 composed of forward extensions of the teeth 23 and which 55 teeth extensions have cutting edges which are curved inwardly and forwardly at 25 in exact conformity with the shape of the fillet on the journal.

In the preferred construction the pilot stem 20 is held by means of the bearing member 30 comprising a plate-like part 31 and an integral substantially semi-cylindrical part 32, the plate being provided with a pair of studs 33 adapted to interfit accurately with the holes 34 of the journal box frame. In

some automobiles, such as the well-known "Ford," the journal box caps are held by two bolts in holes as 34, and these holes are substantially accurately positioned with a line connecting their centers at right angles to the axis of the bearing, this axis being indicated at 35, Fig. 2. A hole 36 is bored in the pilot stem bearing member 30, the hole being coaxial with the bearing surface 37 of the journal box when the pilot stem 70 holder 30 is resting on top of the box 10 with the studs 33 in the holes 34. This hole 36 accommodates the pilot stem 20 with a neat fit for rotation therein.

In using the device of Fig. 1 the babbitt 80 11 is filed away at its top edges 39 (Fig. 2) until these edges are flush with the top of the box. The bearing member 30 is then applied as shown in the drawings and held down firmly upon the journal box with one 85 hand while with the other the pilot stem 20 is inserted in the hole 36 and the cutter is rotated by means of the handle, the cutter being at the same time forced into the work. A few turns of the cutter are sufficient to remove the excess metal 12 and simultaneously 90 cut the fillet way shown at 40, Fig. 5. When the operation is completed at one end of the bearing the cutter is simply withdrawn and inserted in the holder 30 from the other 95 direction and the operation repeated.

According to Fig. 5 the means disclosed for holding the pilot stem 20 are shown as a cylindrical tube or sleeve 41, the outside of which has the diameter of the journal and 100 of the bearing surface 37. The longitudinal hole through the sleeve is coaxial with the bearing and accommodates rotatably the pilot stem 20. In operation the sleeve 41 is held in the bearing directly upon the 105 bearing surface and constitutes an accurate guide and support for the cutter in its desired position.

I claim:

1. In a hand tool for surfacing the end of 110 a journal box, the combination of a cutter formed to remove metal at the end of the box on lines substantially at right angles to the axis of the bearing and also formed to remove corner metal at the end of the box 115 adjacent to the bearing for a fillet on the journal, pilot means coaxial with the cutter and adapted to be held in coaxial arrangement with the bearing, and hand-operable means for rotating the cutter. 120

2. In a hand tool for surfacing the end of 125 a journal box, the combination of a cutter formed to remove metal at the end of the box on lines substantially at right angles to the axis of the bearing and also formed to remove corner metal at the end of the box 130 adjacent to the bearing for a fillet on the journal, a pilot coaxial with the cutter, a bearing member for the pilot, said bearing member being adapted to fit upon the box 130

with the pilot held thereby in coaxial arrangement with the bearing, and hand-operable means for rotating the cutter.

3. In a hand tool for surfacing the end of a journal box, the combination of a cutter formed to remove metal at the end of the box to conform to the shape of the journal which is to bear there upon the box, a shaft

on which the cutter is coaxially and readily removably mounted, one end of the shaft 10 constituting a pilot, a bearing member for the pilot, the bearing member having means for holding it upon the box with the pilot in coaxial arrangement with the bearing, and hand-operable means for rotating the cutter. 15
